US00D506185S

(12) **United States Design Patent** (10) Patent No.: **US D506,185 S**
Kim (45) Date of Patent: **** Jun. 14, 2005**

(54) **CIRCUIT BREAKER FOR PROTECTING MOTOR**

(75) Inventor: **Ho Seong Kim**, Cheongju-shi (KR)

(73) Assignee: **LG Industrial Systems Co., Ltd.**, Seoul (KR)

(**) Term: **14 Years**

(21) Appl. No.: **29/179,355**

(22) Filed: **Apr. 10, 2003**

(30) **Foreign Application Priority Data**

Nov. 5, 2002 (KR) 30-2002-0031505

(51) **LOC (8) Cl.** **13-03**

(52) **U.S. Cl.** **D13/160**

(57) **CLAIM**

The ornamental design for a circuit breaker for protecting motor, as shown and described.

DESCRIPTION

FIG. 1 is a perspective view of a circuit breaker for protecting motor showing the new design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof.

The broken line showing of the environment is for illustrative purposes only and forms no part of the claimed design.
